UNITED STATES PATENT OFFICE.

LEE B. GREEN, OF DETROIT, MICHIGAN, ASSIGNOR TO THE FEDERAL MACHINE PRODUCTS CO., OF CLEVELAND, OHIO, A CORPORATION OF OHIO.

IGNITION-TROUBLE FINDER.

1,352,662.

Specification of Letters Patent. Patented Sept. 14, 1920.

Application filed February 17, 1919. Serial No. 277,468

To all whom it may concern:

Be it known that I, LEE B. GREEN, a citizen of the United States, residing at Detroit, county of Wayne, State of Michigan, have 5 invented a new and useful Improvement in Ignition-Trouble Finders, of which the following is a specification.

This invention relates to ignition trouble finders for internal combustion engines, and 10 has for its object a device which will indicate failure of a circuit through the plugs, trouble in the lead wires from the distributor to the ignition trouble device or back of these wires, or indicate missing of 15 a cylinder, usually due to the shorting of a circuit through a plug.

The device is built so that separate tests 20 may be made to determine the completeness of the circuit through any plug, and separate tests may be made for trouble in any one of the leads from the distributor. This will best be understood when the construction of the device is apprehended.

In the drawings,—

25 Figure 1 is an elevation showing the face of the device.

Fig. 2 is a top plan view with a portion broken away.

Fig. 3 is a detail of one of the spring contact buttons.

Fig. 4 is a detail of one of the plungers.

Fig. 5 is an enlarged section of the bridging sleeve on the plunger.

Fig. 6 is a section showing the plunger 35 set in what is known as the running position.

Fig. 7 shows the plunger set to test the plug out for completeness of the circuit.

Fig. 8 shows the plunger set to ground 40 the current. This serves for determining trouble in the lead from the distributor or back of the same and also serves to indicate missing of a cylinder, as will appear later.

The device is built largely of molded 45 "bakelite" or any other suitable insulating material which is molded about the wires that go to make it up. This bakelite is designated *a*. Secured to the front end of this block of insulating material is a face 50 plate *b* which is provided with a flange *c* that may be secured to the dash of an automobile or any other convenient place. This face plate is provided with a plurality of glazed openings *d* and in recesses back of 55 which terminals form spark gaps *e*. There

is a spark gap and an opening for each cylinder, here shown as six in number. The wire in which this gap occurs terminates in a spring contact button *f* at the side of a bore through the block in which the plunger *g* is slidable. This plunger is made of insulating material, or perfectly hard rubber, and is provided with a bridging sleeve *h* having a pair of annular grooves to seat the various contact buttons.

60 The normal circuit in running position leads from the binding post *i*, to which is attached a distributor lead, through the wire *j* to the spring contact button *k*. Forward of this on the under side of the bore is a contact button *l* that will be called the plug 65 contact button for it connects with a plug wire *m*.

The spark gap *e* is in what will be termed a by-pass circuit *n*. *o* designates a grounded 70 contact button. All these grounded contact buttons are connected by a single bar *p* (Fig. 2) and have a single ground wire *q*.

75 The operation is as follows: The current comes in from the distributor lead to the binding post *i* and when the plunger is at its extreme inward position runs through the wire *j*, the contact button *k*, through the bridging strip *h*, through the plug contact *l* and the plug wire *m* to the spark plug. This 80 is the running position (see Fig. 6). When, after finding that the current comes all right from the distributor, it is desired to test the plugs for failure of circuit through the 85 plugs or their connections, the plunger *g* is pulled out to the second position (see Fig. 7). The current then enters, runs through the by-pass *n*, jumps the spark gap *d* (provided there is a circuit through the plug) 90 and then runs through the by-pass contact *f* to the bridge *h*, the plug contact *l* and plug wire *m* to the plug. If there is no spark at the gap *d* the operator knows there 95 is a failure in the circuit through the plug.

100 When the plunger *g* is pulled out to its extreme outward position (Fig. 8) the current comes into the binding post *i* (provided there is no trouble in the distributor leads or back of the same), runs through the by-pass *n*, jumps the spark gap *d*, goes out the 105 by-pass contact *f*, through the bridge *h*, reaches the ground contact *o*, and then runs through the ground bar *p* and the ground wire *q* to ground. If no spark occurs at the gap *e*, the operator knows there is trou- 110

ble in the distributor leads or back of the same. If no spark occurs in any of the windows *d* the operator knows that the trouble lies in the rotor of the distributor or back 5 of the same, that is, that the current fails at the rotor, some of the connections leading to the rotor, induction coil, the battery, or some of the connections. If the current fails only at one or more of the gaps *e* with 10 the plungers all out to the extreme positions, then the operator knows that the trouble is somewhere between the ignition trouble finder and the distributor rotor in the distributor leads that fail.

15 By successively cutting out the cylinders, one at a time, by this grounding position of the plunger, the operator can tell where the missing of fire occurs in the engine. If a cylinder is not missing, the engine will slow 20 down. When a cylinder is reached that is missing, the engine will continue at the same speed.

It will be apparent from this description 25 that trouble of almost any kind in an ignition system can be located with considerable ease by this trouble finder. The first trouble to test for would preferably be trouble in the rotor of the distributor or back of the same. This can be accomplished by pulling 30 out the plungers simultaneously to their extreme positions. This will tell also whether there is any trouble in the distributor leads. Following this the plugs may be tested either for shorting or failure of circuits in the ways 35 indicated.

When all the plungers are pulled out to extreme positions the engine will have to be turned over with the starter or by crank.

What I claim is:

40 1. An ignition trouble finder for an internal combustion engine, comprising means for indicating trouble in the wires leading from the distributor or back of the same, means for indicating the failure of a circuit 45 through any one of the plugs and capable of separately testing each plug, and means for successively cutting out the plugs to make apparent a missing of any of the cylinders.

2. An ignition trouble finder for an internal combustion engine, having in combination, means for indicating trouble in the wires leading from the distributor and behind the same which includes the grounding 55 of the current led through the trouble device, means for detecting trouble in any one of the plugs in the way of failure of a circuit either by testing each cylinder separately or any number of cylinders together, and means for detecting a missing of any 60 one of the cylinders.

3. An ignition trouble finder, comprising an insulated support, wiring in said support forming a direct electrical connection from a distributor lead to a plug save for a switch 65 interval and for forming a by-pass provided

with an observable spark gap connecting with the plug save for the switch interval, and a switch in said support for bridging the interval in the direct wire to the plug or the interval in the by-pass and disconnecting the direct wire to the plug. 70

4. An ignition trouble finder, having in combination, a support provided with suitable insulation, wiring contained in the support forming an electrical connection between a distributor lead directly to the plug save for a switch interval and forming a by-pass including an observable spark gap to the plug save for a switch interval and forming a ground wire, and a switch contained in the support for bridging the switch interval in the direct line to the plug, for bridging the interval in the by-pass line and disconnecting the direct line and for grounding the current in the by-pass line 80 after it has passed through the spark gap.

5. An ignition trouble finder, comprising a support with suitable insulation, wiring contained in the support and constituting an electrical connection between a distributor lead and a spark plug save for a switch interval, constituting a by-pass through an observable spark gap save for a switch interval and constituting a grounding line for connection with the by-pass, and a sliding 90 plunger provided with a bridging sleeve adapted to bridge the interval in the direct line to the plug, bridge the interval in the by-pass line and disconnect the direct line to the plug and to bridge the interval between the by-pass and the grounding line. 100

6. An ignition trouble finder, comprising a housing block, means with the assistance of switches for leading a current directly to the plugs through the housing block from 110 each distributor wire, means for carrying a by-passed current from each distributor wire, and an independently operable switching member for each distributor wire for controlling the by-passing or the direct passage of the current through the block. 120

7. An ignition trouble finder, comprising a housing block, means with the assistance of switches for leading the current therethrough from each distributor lead to the 130 plugs, means for carrying by-passed current through observable spark gaps, means for carrying the current to the ground, and a separate switch for each distributor circuit to direct the current directly through the 140 trouble device, by-pass the current through the gaps to the plugs, or by-pass the current through the gap to ground.

8. An ignition trouble finder, comprising a housing block, means with the assistance 145 of switches for leading current directly therethrough to the plugs, means for carrying by-passed current to the spark gaps for each distributor circuit, means for carrying the grounded current, and a plurality of 150

- plunger-like switches one for each distributor circuit adapted to occupy three positions, the position compelling the current to go from the distributor lead wires directly to the plugs, the position compelling the current to go through the spark gaps directly to the plugs and the third position compelling the current to go through the spark gaps to ground.
- 5 9. An ignition trouble finder, comprising a block of insulating material having supported therein a plurality of wires forming means in connection with switches for carrying the current directly from the distributor leads to the plugs, means for by-passing the current from each distributor lead through spark gaps, and means for carrying such bypassed current to ground, said wires ending in spring contacts at the sides of bores 10 through the block, said block provided with a bore for each cylinder, and a plurality of switching plungers each made of insulating material, one plunger for each bore, each plunger being provided with a bridging 15 sleeve, whereby the plunger in three separate positions of longitudinal movement allows the bridging sleeve to bridge three separate pairs of contacts, namely, the contacts leading the current directly from the distributor leads to the plugs, second, by-passing the current through the spark gaps to the plugs, and third, by-passing the current through the spark gaps and to ground.
- 10 10. An ignition trouble finder, comprising a housing block of insulating material provided with a bore for each cylinder, wiring within the housing block to form separate conducting lines from each distributor to the plugs except for a switch interval, and for forming a by-pass through a spark gap 35 for each line with the distributor, and for grounding the current from each spark gap, and a plurality of slideable plungers having switching bridges for filling which in three positions of longitudinal movement cause 40 the current to go directly through the switching block from the distributor lead to the plug, cause the current to be by-passed through the spark gap to the plug, or cause the current to be by-passed from the distributor lead through the spark gap and grounded.
- 45 In witness whereof I have hereunto set my hand on the 10th day of February, 1919.
- 50 LEE B. GREEN.
